Primary Examiner — Karen S Acker(74) *Attorney, Agent, or Firm* — Nelson Mullins Riley & Scarborough LLP(57) **CLAIM**

The ornamental design for a nonwoven fabric, as shown and described.

DESCRIPTION

FIG. 1 is a bottom left perspective view of a nonwoven fabric, embodying the new design;

FIG. 2 is a top plan view thereof;

FIG. 3 is a rear plan view thereof; and,

FIG. 4 is a cross-sectional view thereof taken along the line 4-4 of FIG. 2.

The broken lines surrounding the figures depict the boundaries of the claim and form no part thereof.
